UNITED STATES PATENT OFFICE.

EDWARD B. BLAKELY AND RUFUS B. MCCOLLUM, OF KANSAS CITY, MISSOURI.

PNEUMATIC JACK FOR MOTOR-CARS.

1,130,884.

Specification of Letters Patent.

Patented Mar. 9, 1915.

Application filed November 20, 1913. Serial No. 802,073.

To all whom it may concern:

Be it known that we, EDWARD B. BLAKELY and RUFUS B. MCCOLLUM, citizens of the United States, residing at Kansas City, in the county of Jackson and State of Missouri, have invented certain new and useful Improvements in Pneumatic Jacks for Motor-Cars, of which the following is a specification.

10 This invention relates to pneumatic jacks designed principally for use with motor cars, and one object in view is to provide an apparatus adapted to be attached permanently to the car and in readiness for 15 operation by simply turning on a valve or valves whenever it is desired to jack the vehicle.

20 A further object is to produce a pneumatically operated apparatus by means of 25 which either a portion only of the car may be jacked or the whole car may be elevated bodily off the ground.

The invention further comprises a peculiar 25 form of pneumatic cylinder employed for each of the jacking units, in which cylinder a piston having a novel telescoping action is used.

With these objects in view the invention 30 consists in certain novel and peculiar features of construction and organization as hereinafter described and claimed, and in order that it may be fully understood reference is to be had to the accompanying drawing, in which—

35 Figure 1, is a plan view of the running gear of a motor car showing the application of our improvements thereto. Fig. 2, is a longitudinal section through one of the jacks. Fig. 3, is a fragmentary side view 40 of one of the jacks equipped with a connection broken away. Fig. 4, is a cross section of one of the valves. Fig. 5, is a vertical section through the rear axle adjacent one of the jacks and showing a broken portion 45 of the latter in elevation. Fig. 6, is a horizontal section through one of the jacks.

Referring to the drawing, each jack comprises a cylinder 2 having an inlet pipe 4 and an exhaust pipe 6, both of which pipes 50 communicate through a two-way valve 8 with a short pipe 9. The pipes 9 lead to a common pipe 10, communicating with a compressed air storage tank 12. The pipe 10 is also equipped with a valve 14. Each of the 55 cylinders 2 of the front jacks is provided with a suitable boss 16 for securing the cyl-

inder to the front axle 18 adjacent the steering knuckles, while the cylinders of the rear jacks are provided with bosses 20 recessed as shown in Fig. 5 for embracing the housing 22 surrounding the rear axle 23. Clamping brackets 24 are used to secure the bosses 20 to said housing, said bosses being further provided with studs 26 projecting through suitable openings in the housing to insure holding of the cylinders in vertical position.

Within each cylinder operates a telescoping piston (see Figs. 2 and 6) comprising a cylinder 28 and piston rod 30, the combined length of which is sufficient to jack the corresponding portion of the car off the ground. The cylinder 28 and rod 30 each has a piston head suitably secured to its upper end and comprising rings 32 and 75 disks 34 respectively rendered tight fitting by means of suitable packing 36. The piston head carried by the cylinder 28 fits the interior of the cylinder 2, while the other piston head is fitted air tight within the cylinder 28. Stuffing boxes 38 and 40 are provided at the lower ends of the cylinders 2 and 28 respectively, to accommodate the sliding action of such cylinder 28 and rod. The cylinder 28 is provided with a plurality 80 of side openings 42 near its lower end, and a collar 44 is secured to the rod 30 far enough below the piston head of said rod to strike the bottom of cylinder 28 to prevent the same from ever closing the openings 42. 90

Similarly a suitable collar 46 is secured to the cylinder 28 near its upper end to engage a part of the stuffing box 38 and thereby prevent the piston head from closing the opening into the pipe 6, while a flange of 95 said cylinder 47 is formed on the lower end of said cylinder to limit its rising movement by engaging the said stuffing box to prevent closing of the opening into pipe 4.

A foot piece 48 is carried by the lower end 100 of each rod 30 and to the latter is also fixed a rod 50 extending upward alongside the cylinder 2 and through a guide block 52. A latch bolt 54 is mounted in the block 52 and is adapted to be slipped over the top of the 105 rod 50 after the jack has been fully extended and thereby hold the jack in operative position regardless of any leakage of air past the pistons, it being understood that these rest rods 50 of the cylinders are designed 110 for use particularly when the machine is allowed to remain jacked over night.

In operation one or more of the jack cylinders may be brought into use by proper manipulation of the valves 8, the cylinders being normally in collapsed condition as shown in Figs. 2 and 3. The valve of each cylinder to be operated is so turned as to place its pipe 4 in communication with the corresponding pipe 9, and the pipe 6 with the exhaust opening 56, as shown in Fig. 4, while the valves of the remaining cylinders will simply be turned to close all of the valve ports. Next the valve 14 of the pipe 10 is opened to admit air from the tank 12 into the pipes 9 and through the open valves into the pipes 4 of the cylinders to be operated. The pressure operates the pistons of said cylinders, lowering each cylinder 28 until its collar 46 is seated adjacent the opening into pipe 6. Next the piston head of each rod 30 is operated within the corresponding cylinder 28, forcing the air within out through the openings 42. This action of the rod 30 will bring the foot piece in contact with the ground and thereafter the relative movement of the piston rod and cylinders will cause the car or that portion thereof being jacked, to be lifted off the ground. In this position the upper ends of the rods 50 will lie beneath the level of the bolt 54. The valve 14 is then closed and in the event that the car is to be left in this position for a considerable length of time, the bolts may be turned into place over the rods so that the weight of the car will be brought upon the rest rods thus preventing reseating of the pistons through leakage of the air. When it is desired to unjack the cylinders, the bolts 54 are retracted and the appropriate valves are turned to place the pipes 4 of the corresponding cylinders in communication with the exhaust openings 56, and pipes 6 in communication with the pipes 9. The valve 14 is then again opened whereupon the cylinders 28 are raised by air entering from pipes 6 into cylinders 2, as soon as the openings 42 are brought into communication with the cylinders 2, the piston heads of rods 30 will be actuated to raise the latter, the parts coming to rest in original position as shown in Fig. 2.

From the foregoing it will be apparent that while we have illustrated and described what we now consider the preferred embodiment of the invention, obvious changes will suggest themselves to one skilled in the art, and we do not desire to be restricted to the exact details of construction shown but reserve the right to make all changes falling

within the spirit and scope of the appended claims.

We claim:

1. In a pneumatic jack, the combination of a cylinder having compressed air inlet and outlet openings, a second cylinder within the first cylinder and provided with a piston head engaging the same, a rod extending through the second cylinder and provided with a piston within the latter, a head secured to the lower end of the rod and provided with a rod extending parallel with and externally of the first-named cylinder, a block secured to the said first-named cylinder, through which said last-named rod slidingly extends, and a latch bolt carried by said block and adapted to be fitted over said rod when the jack is fully extended. 60
2. In a pneumatic jack, the combination of a cylinder having compressed air inlet and outlet openings adjacent its opposite ends respectively, a second cylinder within said first cylinder and spaced therefrom, the inner end of said second cylinder being open, an annular piston head carried by said inner end, and bridging the space between the cylinders, means confining said piston head to movement between said openings, said second cylinder being provided with openings communicating with said space between the cylinders when the latter are telescoped, and a rod provided with a piston operating within said second cylinder under pressure transmitted through said last-named openings and the inner end of said second cylinder respectively. 75
3. In a pneumatic jack, the combination of a cylinder having compressed air inlet and outlet openings, a second cylinder provided with a piston rod operating within said first cylinder, a rod provided with a piston actuated within said second cylinder by means of pressure transmitted through said openings, a foot piece secured to the exterior end of said rod, a rod fixed to said foot piece and extended upward alongside said first cylinder, and means carried by the latter for engaging said second named rod and maintaining said cylinders and piston rod in extended position after shutting off the compressed air supply. 90

In testimony whereof, we affix our signatures, in the presence of two witnesses.

EDWARD B. BLAKKEY.
RUFUS B. McCOLLUM.
